TAPPET ADJUSTING TOOL

Joseph Hammond, Rockford, Ill.

Application December 7, 1946, Serial No. 714,711

7 Claims. (Cl. 81—3)

1

This invention relates to tappet adjusting tools designed to facilitate the adjustment of tappets on valve-in-head engines, such as are used on Buicks and Chevrolets, these tools being, however, usable also wherever a similarly locked screw adjustment is employed.

The principal object of my invention is to provide a tappet adjusting tool of relatively simple and inexpensive construction and substantially universally adaptable for use in adjusting the different sized tappet screws on engines of various sizes and used on different makes of cars.

A salient feature of my tappet adjusting tool is the provision of a centering sleeve cooperating with the screw driver bit to fit over the end of the screw and facilitate engaging the bit in the slot, together with a hold-down sleeve which rests on top of the wrench that is applied to the lock nut, whereby to hold the wrench securely throughout the adjusting operation so long as the operator has hold of the handle of the screw driver and keeps the screw driver bit pressed down into the slot, thus enabling the operator to let go of the wrench while checking the tappet adjustment with a feeler gauge.

In the preferred form the centering sleeve is separate from and has a telescoping fit in the hold-down sleeve, and there is a relatively light coiled compression spring acting between the sleeves urging the centering sleeve in an outward direction, there being another relatively heavy coiled compression spring acting between the handle and the hold-down sleeve urging that sleeve in an outward direction. The latter spring may be backed up by an adjusting nut threaded on the shank of the screw driver bit to enable adjusting the hold-down sleeve endwise relative to the centering sleeve to compensate for differences in the extent to which the adjusting screw projects from the lock nut. On the other hand, I may provide a hook member slidably on the shank behind said spring and arranged to be hooked under the rocker arm so as to compress the spring and hold the tool in assembled working relation to the adjusting screw and the wrench on the lock nut on the rocker arm, and thereby relieve the operator of the necessity of applying the necessary downward pressure on the handle, the heavier spring being kept compressed by the hook member to keep the hold-down sleeve holding the wrench in place and applying spring pressure through the other spring on the centering sleeve to keep it in operative relationship to the screw.

The invention is illustrated in the accompanying drawing, in which

2

Fig. 1 is a longitudinal section through a tappet adjusting tool made in accordance with my invention and shown in working position;

Fig. 2 is a view similar to the lower portion of Fig. 1, but illustrating a modification; and

Fig. 3 is a view taken on the line 3—3 of Fig. 2. Similar reference numerals are applied to corresponding parts throughout the views.

The reference numeral 5 designates the shank of the tool on the lower end of which the screw driver bit 6 is formed, adapted to be entered in the screw driver slot 7 provided in the upper end of the adjusting screw 8 that is threaded in the usual way in one end of a rocker arm 9 for adjustment of the tappets on a valve-in-head engine. While I have shown a screw driver bit of conventional shape, it will be understood I may provide one adapted to work in a criss-cross slot, or one of hexagonal form to work in a hex socket. As is well known, the rocker arms 9 oscillate with respect to a shaft 10 to depress the stems of the valves in the head, the end of one of which stems is indicated in dotted lines at 11, to open these valves against the action of their springs. The rocker arms 9 are operated by push rods which have separate floating upper end sections 12 that have sockets in their upper ends cooperating with the spherical lower ends 13 of the adjusting screws. When a given valve is closed and the engine is operating at normal running temperature, there should be a certain small amount of clearance measurable with a feeler gauge between the finger 14 of the rocker arm 9 and the end of the valve stem 11. In adjusting a tappet, the lock nut 15 threaded on the upper end portion of the screw 8 must be loosened first so that the screw can be turned one way or the other for adjustment relative to the rocker arm 9, and, considering the fact that the adjustment is usually made with the engine idling, it is obviously rather awkward to loosen and tighten the nut 15 and adjust the screw 8 and, between the loosening and tightening of the nut 15, check the clearance with the feeler gauge while holding the screw 8 in an adjusted position, all while the engine is running.

The tappet adjusting tool of my invention simplifies the operation principally by holding the wrench 16 in place on the nut 15 while the clearance is being checked with the feeler gauge, the operator using one hand to hold the tappet adjusting tool by means of the handle 17 and holding the feeler gauge with the other hand. Then, as soon as the correct clearance has been obtained, the wrench 16 can be turned to tighten the nut 15 while the screw 8 is held by means of the screw driver bit 6.

The tool, in accordance with my invention, comprises a centering sleeve 18 slideable freely on the enlarged cylindrical lower end portion 19 of the shank 5, and a hold-down sleeve 20 slideable freely on the outside of the centering sleeve 18, the sleeve 18 having an inwardly directed annular flange portion 21 on its upper end which is arranged to have abutment with the annular shoulder 22 defined on the top of the enlarged portion 19, and the sleeve 20 having an inwardly directed annular flange 23 which serves as an abutment for a coiled compression spring 24 disposed inside the upper end portion of the sleeve 20 and bearing against the upper end of the sleeve 18 to urge the sleeve 18 normally downwardly relative to the screw driver bit 6, so that the flared lower end portion 25 of the bore of the sleeve 18 will cooperate with the upper end of the screw 8 to center the tool with respect to the screw 8 and thereby facilitate entering the bit 6 in the slot 7 of the screw. The flare 25 terminates in a counterbore 26 which is large enough in diameter to accommodate the largest sized adjusting screws 8 so that this one tool can be used substantially universally for tappet adjusting work and for other screw adjustments. The spring 24 is relatively light, and there is a relatively heavy coiled compression spring 27 surrounding the shank 5 above the sleeve 20 between the handle 17 and the sleeve serving to press the sleeve 20 down firmly on top of the socket end 28 of the wrench 16 disposed in engagement with the nut 15, whereby to hold the wrench in engagement with the nut under a relatively heavy spring pressure so long as the tool is in position for tappet adjustment. The lower end 29 of the sleeve 20 is enlarged radially sufficiently to engage the tops of wrenches of various diameters required with different sized nuts 15. Now, it is obvious that in some cases the screw 8 projects farther from the top of the nut 15 than in others, and in order to adjust the sleeve 20 bodily relative to the sleeve 18 in either direction quickly, I have provided an adjusting nut 30 threaded on the threaded turns of this nut in one direction or the other will be enough to adjust the sleeve 20 to whatever small extent may be necessary, the spring 24 in a downward adjustment of the sleeve 20 being easily compressed as the heavier spring is adjusted downwardly by the nut 30, and vice versa. The threaded upper end portion 31 of the shank 5 has diametrically opposed fins or splines 32 extruded therefrom to stake the shank 5 in the bore 33 of the handle 17 to prevent turning of the handle relative to the screw driver bit 6 in an adjusting operation.

In Fig. 2, I have shown a hook 34 which is arranged to be engaged under the outer end portion of the rocker arm 9 next to the screw 8 to hold the tappet adjusting tool in operative position with the spring 27 compressed by the right angle upper end portion 35 of the hook member, which has a loose fit on the shank 5a and bears on the upper end of the spring 27, thereby relieving the operator of the necessity of pressing downwardly on the handle 17a. The only thing the operator has to do is to hold the handle 17a and turn it one way or the other to adjust the screw 8 if the feeler gauge indicates a need for an adjustment to increase or decrease the valve operating clearance. In applying this tool, the hook 34 is hooked under the rocker arm 9 first and then the handle 17a is raised against the resistance of spring 27 far enough to permit

bringing the lower end of the tool into position over the screw 8 and nut 15, after which the tool is applied similarly as above described, the compressed spring 27 in this case serving to urge the tool toward the screw and nut to facilitate the application of the tool and thereafter hold the tool in the operative position. It is, therefore, far less fatiguing to the operator to work with this tool because he does not have to bear down on it against the resistance of the spring 27 to keep the tool in the operative position.

It is believed the foregoing description conveys a good understanding of the objects and advantages of my invention. The appended claims have been drawn to cover all legitimate modifications and adaptations.
